J. B. HOGE ET AL.

RADIOPHONE METER

Original Filed Sept. 8, 1922

UNITED STATES PATENT OFFICE.

JAMES B. HOGE, OF CLEVELAND, OHIO, AND EDWARD E. CLEMENT, OF WASHINGTON, DISTRICT OF COLUMBIA, ASSIGNEES, BY DIRECT AND MESNE ASSIGNMENTS, TO EDWARD F. COLLADAY, OF WASHINGTON, DISTRICT OF COLUMBIA.

RADIOPHONE METER.

Original application filed September 8, 1922, Serial No. 586,842. Divided and this application filed August 18, 1924. Serial No. 732,797.

Our invention relates to radiophone systems, and has for its object the combination of such a system with an electric light, power, or railway system, so that the wires 5 of said system may be employed for metering. This application is a division of our prior copending application, Serial No. 586,842, filed September 8, 1922.

In the present case, we attain our object by locating a standard type of radiophone receiving instrument at consumers' stations on an electric light, power, telegraph or railway system, and broadcast from a central station, which may be the 15 central power station or a substation belonging to the system. At the radiophone stations, we provide switching connections from the instruments to the current mains, and through these connections effect current 20 feed to the filament and plate circuits and for metering. The central station is provided with amplifying and modulating apparatus for original matter, and with relay apparatus for distributing to the subscribers or local consumers programmes 25 and other matters received from a distance. By thus organizing the system so that the subscribers are dependent solely on their local central station for all radio communication, it is possible to unify the service in 30 all respects, and to make metered service charges on a fair and accurate basis.

It is to be understood that the principles herein set forth are not limited as to their 35 embodiment to lighting, power or railway circuits as such, but that any conductor or wire circuit capable of carrying and supplying the necessary current and performing the functions described herein, may be used 40 in the present invention, and the related inventions hereinbefore referred to. Among such conductors are telegraph lines, trolley wires, feed wires and cable of lighting, power and railway systems, third rails and 45 underground trolley conductors, and fence and tree wires used by ranchers, lumber interests and others in sparsely settled districts.

Our invention is illustrated in the accompanying drawing, in which:

The figure is a typical diagram showing a radiophone station and the connections to a central power station.

Referring to the drawing we have therein shown a portion of a system of power and 55 communication circuits, one radiophone RR, and the general arrangement of a radio operator's switchboard for connecting up the communication circuits.

The feeder M^2 extends from transformer 60 substation C' to the house transformer K' which supplies main M' carrying lamps L . To this main a socket is connected with which a plug P cooperates to connect the feed wires 17-18 of the radiophone receiver RR. Current for filament and plate 65 circuits for the loud speaking receiver, and for the meter RM is supplied through this circuit. The meter may be of any standard type adapted to the current employed. In 70 the present case alternating current at 60 cycles, single phase, is presupposed.

The receiving instrument RR is equipped with antenna 25^a, coupler 28, etc., as usual. On the audio side, transformer 14 supplies 75 the armature of the loud speaking receiver 56, its field being fed direct from wires 17-18.

In operation, a subscriber desiring radio service, plugs his set in on the line M' 80 through means of the plug P , which supplies power to his receiving set RR through conductors 17-18 and to the meter 22 through branch wires 19-20. The meter therefor starts into operation and continues to 85 record the length of time the connection is maintained. The receiver RR, being supplied with power will now pick up the broadcast signaling to which it is tuned through the antenna circuit 25^a-28 and 90 translate it into amplified audible signals through the transformer 14 and loud speaker 56 in a manner which will be understood by those skilled in the art. In the present instance the receiver RR is tuned to the transmitting station RT so that broadcast matter 95 is received therefrom.

We claim:

1. In a system of the class described, a central power distributing station and a current supply circuit extending from said power station to consumer stations, a consumer station connected with said supply circuit, permanently connected outlets from said circuit in said consumer station, power 100 translating devices adapted to be connected 105

- through said outlets to said supply circuit, a radio receiving set at said consumer station having an energizing circuit, a time use meter, and a meter motor with a driving circuit therefor, switch terminals connected to both said energizing circuit and to said meter motor circuit, forming a single inseparable terminal unit adapted to be connected to and disconnected from said outlet terminals at will, whereby the radio receiving set is normally entirely disconnected from said power supply circuit, and cannot be connected thereto for power supply for its operation without also connecting and operating its meter motor to record its time use. 25
- 5 10 15
2. In a system of the class described, a central power distributing station and a current supply circuit extending from said power station to consumer stations, a consumer station connected with said supply circuit, permanently connected outlets from said circuit in said consumer station, power translating devices adapted to be connected through said outlets to said supply circuit, a radio receiving set at said consumer station having an energizing circuit, a time use meter, and a meter motor with a driving circuit therefor, a pair of switch terminals connected to both said energizing circuit and to said meter motor circuit, in parallel, 30 forming a single inseparable terminal unit adapted to be connected to and disconnected from said outlet terminals at will, whereby the radio receiving set is normally entirely disconnected from said power supply circuit, 35 and cannot be connected thereto for power supply for its operation without also connecting and operating its meter motor to record its time use, and whereby also the power consumption of the meter motor is independent of the power supplied to energize the radio receiving elements, and variations in either will not affect the other, said motor being adjusted for constant speed. 40
- 20
- 10 15 20 25 30 35 40

In testimony whereof we hereunto affix our signatures.

JAMES B. HOGE.
EDWARD E. CLEMENT
